UNITED STATES PATENT OFFICE.

JOHN DIAZ ATWOOD, OF MARION, ILLINOIS.

TURBINE.

Application filed October 7, 1925. Serial No. 61,091.

To all whom it may concern:

Be it known that I, JOHN DIAZ ATWOOD, a citizen of the United States, residing at Marion, in the county of Williamson and 5 State of Illinois, have invented certain new and useful Improvements in a Turbine, of which the following is a specification.

This invention relates to a steam propelled vehicle and has for its prime object to provide highly novel propelling mechanism which may be compactly and conveniently arranged on the chassis of the vehicle.

Another very important object of the invention is to provide an improved turbine 15 which is simple in its construction, efficient and reliable in its operation, strong, durable, and otherwise well adapted to the purpose for which it is designed.

Another very important object of the invention is to provide in a vehicle a drive shaft having a pair of turbines oppositely associated therewith for driving the shaft in opposite directions and the provision of conveniently operated control means.

With the above and numerous other objects in view as will appear as the description proceeds, the invention resides in certain novel features of construction and in the combination and arrangement of parts 30 as will be hereinafter more fully described and claimed.

In the drawing

Figure 1 is a top plan view of a vehicle embodying the features of my invention,

Fig. 2 is a vertical section through one of the turbines,

Fig. 3 is a section through said turbine taken substantially on the line 3-3 of Fig. 2, looking in the direction of the arrows,

Fig. 4 is a plan view looking at the edge of one of the rotors,

Fig. 5 is a fragmentary detail elevation of one of the rotors, and

Fig. 6 is a detail section taken through one end of the steam manifold and the valves therein.

Referring to the drawing, in detail, it will be seen that the numeral 5 designates the chassis of the vehicle which is mounted in any suitable manner on the wheels 6 and 7, the latter of which are driven through the mechanism 8 operable by the drive shaft 9. A fuel tank 10 is located on the rear end of the chassis, a water tank 11 is disposed between the ends of the chassis, a boiler 12 is disposed adjacent the front end

of the chassis, and a condenser 13 is disposed at the front end of the chassis.

The fuel tank 10 is connected with the burners 14 of the boiler 12 by pipes 14 60 The water tank 11 communicates with the boiler 12 through the pipes 15. A pair of turbines 17 and 18 are mounted in any suitable manner in the chassis 5 between the tank 11 and the boiler 12. The turbine 17 65 is constructed to propel the vehicle forwardly while the turbine 18 is designed to propel the vehicle rearwardly. From a structural standpoint, and principles of operation, the turbines are practically identical and a detailed description of one will suffice for both. The turbine structure is illustrated to advantage in Figs. 2 to 5 inclusive.

Referring in detail to the turbine 17, it 75 will be seen that the same includes among other elements to be mentioned later, a casing 19 having a circular outer wall, a fixed side wall 20 and a removable side wall 21. The drive shaft 9 is journaled centrally 80 through the walls 20 and 21. This casing 19, of course, is stationarily mounted in relation to the chassis 5. The outer wall of the casing is provided with a plurality of outlets indicated at 23 from which extend 85 pipe sections 24 leading alternately through walls 20 and 21 adjacent the outer wall. The exhaust pipe is shown at 26 and the intake pipe is shown at 27. This intake pipe 90 27 leads through the wall 20 tangentially to the axis of the casing. The rotor 28 is of circular construction and is keyed to the shaft 9 as at 29. The outer periphery or edge of the rotor 28 is provided with a plurality of V-shaped pockets 30 formed by a 95 plurality of spaced V-shaped fins 31. A plurality of radially disposed pockets 32 are formed on the sides of the rotor adjacent the edge thereof, two of said pockets 32 being disposed in registry and in communication with each pocket 30.

The steam passing inwardly of the casing through the pipe 27 impinges against the fins 33 forming the pockets 32, thereby tending to impart rotary motion to the rotor. Referring particularly to Fig. 2 it will be seen that the steam which impinges against one of the fins 30 will expand in the pocket 32 adjacent thereto up into the adjacent pocket 30 and as the rotor advances in a 100 clock-wise direction said steam will partially expand and pass through the first outlet 23 110

and pass through the pipe 24 for again impinging against one of the fins 33 on one side of the rotor. The steam which remains in the pocket 30 when it reaches the next outlet 23 will proceed through the next pipe 24 for impinging against one of the fins on the other side of the rotor and so on around until the steam finally escapes through the pipe 26, after the expansion power thereof has 10 been fully dissipated.

The pipe 27 associated with the rotor 18 leads from one of the valves 35 in the manifold 36. The pipe 27 from the other turbine 17 leads from the valve 37 at the other end 15 of the manifold 26. The manifold 26 is connected to the boiler by the pipes 38. The exhaust pipes 26 merge into a common pipe 39 which leads to the condenser 13.

The valves 35 and 37 are identical in construction and a full understanding of these valves may be had from an inspection of Fig. 6. I shall describe valve 35 in detail only since the other valve is identically constructed.

Referring to this valve 35, as illustrated in Fig. 6, it will be seen that 40 represents a cylinder closed at one end as at 41, while the other end is provided with an outwardly disposed flange 42 having its annular edge 30 threaded for threadedly engaging the threaded opening 43 provided in the manifold 36. The cylinder 40 is provided with an opening 44 and a pipe 45 extends through the cylinder 40 at a point diametrically opposed to the opening 44 and leads upwardly through the flange 42 and merges or is coupled in any suitable manner to the pipe 37. A plunger 46 is slideable in the cylinder 40 and has a transverse opening 47 so that by 35 pressing the plunger downwardly, this opening 47 may be brought into registry with the opening 44 and the open end of the pipe 49. A suitable stuffing box 48 is provided on the open end of the cylinder 40 and a packing 45 nut 49 is associated therewith. A pin 50 extends transversely through the plunger 46 and a spring 51 impinges against said pin 50 and against the flange 42 for normally holding the plunger in its raised position.

The outer ends of the plungers 46 are located within easy access of the feet of the driver of the vehicle. By using the right foot, for instance, on the right hand plunger 46 of the valve 35, the steam may be fed to 50 the reverse turbine 18 for driving the vehicle rearwardly. By using the left foot on

the other valve the steam may be fed to the forward turbine 17 for driving the vehicle forwardly.

The arrangement of the elements on the chassis affords a very well balanced vehicle and allows the easy access to be had to the various parts when desired. The present embodiment of the invention, however, has been disclosed merely by way of example, since in 60 actual practice it attains the features of advantage enumerated as desirable in the statement of the invention and in the above description. Numerous changes in the details of description and in the combination and 65 arrangement of parts may be resorted to without departing from the spirit or scope of the invention as hereinafter claimed or sacrificing any of its advantages.

Having thus described my invention, what 70 I claim as new is:—

1. A turbine of the class described including a casing, a rotor in the casing, said rotor provided with peripheral fins and side surface fins for forming peripheral pockets and 75 pockets in the side surfaces communicating with the peripheral pockets, means for impinging steam against the side pockets, outlets extending from the periphery of the casing, and pipes leading from said outlets alternately to the two sides of the casing for allowing expanding steam to impinge the side pockets.

2. A steam turbine including a circular casing having an annular wall and a pair of disk side walls, outlets provided on the annular wall, said side walls provided with openings adjacent the annular wall, pipes leading alternately from the outlets to the 80 openings in the side walls, means for taking off steam from one of the outlets, and a rotor in the casing.

3. A steam turbine including a circular casing having an annular wall and a pair of disk side walls, outlets provided on the annular wall, said side walls provided with openings adjacent the annular wall, pipes leading alternately from the outlets to the 85 openings in the side walls means for taking off steam from one of the outlets and a rotor in the casing, said rotor being in the form 90 of a disk having pockets formed on its side surfaces adjacent its periphery and pockets formed on its periphery communicating with the other pockets.

In testimony whereof I affix my signature.

JOHN DIAZ ATWOOD.
